INVENTOR.
CHARLES E. BURSSE.

BY

Elliott Stoddard
ATTORNEY.

UNITED STATES PATENT OFFICE

CHARLES E. BUYSSE, OF DETROIT, MICHIGAN

FURNACE

Application filed August 19, 1930. Serial No. 476,348.

My invention relates to furnaces and an object of my improvements is to provide an apparatus of improved structure and operation in which the articles to be heated are thoroughly subjected to gas of uniform temperature throughout its volume, and that is easily regulated.

I attain this object in the apparatus illustrated in the accompanying drawings in which:—

Figure 1 is an elevation partly in section of an apparatus embodying my invention.

Figure 2 is a detail section on the line II, II, Figure 1.

2, 2 is the casing having a passage 3 with a valved loading aperture 6 at one end and a valved delivery opening 7, at the other end.

4 is the carrier belt passing through the passage 3 which may be actuated by suitable machinery 5.

9 is a fan operated by a motor 9a. 11 is a combustion chamber having delivery apertures 11a through its wall and burners 12 in said chamber.

8 is a conduit leading from the loading end 6, of the passage 3 to the intake to the fan 9 and having a controlling valve 8a therein. 10 is a conduit leading from the delivery port of the fan 9 upward and forward and then passing downward adjacent to the wall of the combustion chamber 11 and opening at 10b to the passage 3, about three quarters of the way toward the delivery end of said passage.

The conduit 10 is contracted at 10a adjacent to the delivery passage 11a of the combustion chamber 11, and is provided with openings 10c communicating with the delivery passage 11a. 13 are pieces of metal bent into the inverted U-form, shown in Figure 2, and extending across the throat or contracted part 10a of the passage 10. These are welded at their edges to the sides of the conduit 10 and form partitions between which, and between

45 which and the sides of the conduit, passages for gas are left, as shown in Figure 2.

14 is a conduit opening to the passage 3 at the delivery end thereof passing upward and above the combustion chamber 11 and communicating with the conduit 8 adjacent

to the intake to the fan 9. 14a is a valve in the passage 14.

The passage 3 is provided along its lower wall with inverted-V-shaped partitions 3b extending laterally across the same and upwardly to a little less than half way to the upper wall. The peak of one of these partitions comes below the center of the delivery opening 10b from the conduit 10. The upper wall of the passage 3 is provided with truncated inverted-V-shaped depressions between the salient partitions 3a which alternate with the entirely similar partitions 3b of the lower wall of said passage. By this construction of the passage 3, the gases are constrained to pass alternately downward through the carrier 4 and upward through the same, so that articles on said carrier shall be thoroughly subjected to the hot gas.

The operation of the above described apparatus is as follows:

The fan 9 being set in motion and the burners 12 being in operation, gas is drawn from the loading end of the passage 3 into the fan 9 and forced out through the passage 10 and the contracted portion 10a thereof, thus drawing the hot gas from the combustion chamber 11 through the delivery apertures 11a and the receiving apertures 10c of said conduit. The hot gas from the combustion chamber 11 is, by the action of the jets, adjacent to the portion 10a of the passage 10, thoroughly mingled with the gas passing through said conduit, and is forced into the passage 3 and past the articles approaching from the loading end 6 to which articles the gas gives up its heat to a considerable extent and is then taken through the conduit 8 to the fan 9 and again passed through the passage 10. A portion of the gas discharged from the conduit 10 at 10b may pass toward the delivery end of the passage 3 and may be drawn through the conduit 14 back to the intake to the fan 9. The amount of gas passing through the conduits 8 and 14 may be regulated by the valves 8a and 14a.

In the above described apparatus it is found that the temperature of the gas is uniform throughout its volume and that the

temperature of the gas may be easily and accurately regulated.

The lateral openings 10c come severally directly below the partitions 13 at a point where the passage for the gases is enlarged, and directly at the side of the jets of gas passing between said partitions.

What I claim is:—

1. In an apparatus of the kind described, the combination of a casing having a passage therein having a loading and a delivery end, a conduit communicating with said passage at a point adjacent to the loading end thereof, and at a point part way to the delivery end of said passage, a fan in said conduit adapted to draw gas from the first mentioned point and deliver the same to the other of said points, means for raising the temperature of the gas passing through said conduit, and a second conduit communicating with said passage between the delivery end of the first named conduit and the delivery end of said passage and with the intake of said fan.

2. In an apparatus of the kind described, the combination of a combustion chamber, a conduit for gas, a plurality of spaced partitions 13 in said conduit, and passages from said combustion chamber communicating severally with said conduit at points adjacent to said partitions on the side thereof toward which said gas is moving, and in line with said partitions.

3. In an apparatus of the kind described, the combination of a casing having a passage therein having a loading and a delivery end, a conduit communicating with said passage at a point adjacent to the loading end thereof, and at a point part way to the delivery end of said passage, a fan in said conduit adapted to draw gas from the first mentioned point and deliver the same to the other of said points, means for raising the temperature of the gas passing through said conduit, and a second conduit communicating with said passage between the delivery end of the first named conduit and the delivery end of said passage and with the intake of said fan, and a regulating valve in one of said conduits.

4. In an apparatus of the kind described, the combination of a casing having a passage therein having a loading and a delivery end, a conduit communicating with said passage at a point adjacent to the loading end thereof, and at a point part way to the delivery end of said passage, a fan in said conduit adapted to draw gas from the first mentioned point and deliver the same to the other of said points, means for raising the temperature of the gas passing through said conduit, and a second conduit communicating with said passage between the delivery end of the first named conduit and the delivery end of said passage and with the intake of said fan, and a regulating valve in each of said conduits.

5. In an apparatus of the kind described,

the combination of a combustion chamber, a conduit for gas, a plurality of spaced partitions, 13, in said conduit, and a passage from said combustion chamber communicating with said conduit at a point of reduced cross sectional area on the side of said partitions toward which said gas is moving.

In testimony whereof, I sign this specification.

CHARLES E. BUYSSE.
